GOLF CLUB

Filed Oct. 8, 1928

UNITED STATES PATENT OFFICE

HERBERT C. LAGERBLADE, OF BRISTOL, CONNECTICUT, ASSIGNOR TO THE HORTON MANUFACTURING COMPANY, OF BRISTOL, CONNECTICUT, A CORPORATION OF CONNECTICUT

GOLF CLUB

Application filed October 8, 1928. Serial No. 311,201.

This invention relates to improvements in golf clubs and particularly to a novel method of attaching handle shafts to the club head and a novel form of such connection. The invention is particularly adapted for use in attaching golf club shafts of metallic tubular type to metallic golf club heads.

In the present form of attachment an adapter is utilized, such adapters being now quite common in the art. Described generally, they consist of a tubular sleeve that projects partly without the hosel of the club head and partly within said hosel, the adapter surrounding the handle shaft and insuring a neat fit of the shaft to the hosel. One feature of the present invention is a form of connection between the handle shaft and the club head wherein the means for attaching the shaft to the head does not engage the adapter. This is important because, that where the fastening means, usually a rivet for attaching the shaft in the head extends through the adapter as well as the shaft, it tends to weaken the adapter and often times results in the splitting of the same. With the new form of connection and the new method constituting the present invention, this rivet or other fastening means for the shaft does not extend through the adapter.

Another feature of the present invention is the formation of securing means for attaching the adapter in the club head integrally with said adapter. In other words, the adapter has integrally formed means for securing it in the club head and the securing means for attaching the shaft proper are spaced from or independent of said adapter so that no fastening means of any nature project through the adapter.

Another object contemplated by the present invention is the formation of the adapter in situ in the hosel of the club head.

More specifically, the invention consists in forming in the hosel of the club head an axial bore whose inner portion is of reduced diameter conforming to the diameter of the shaft B attached to said head. In the wall of said hosel near the outer end of said axial bore there is formed a series of recesses and in applying the shaft to the head a mandrel, or

the like, whose cross-section is the same as that of the shaft to be installed, is inserted in the axial bore, being received in that portion of the bore of minor diameter. A plastic material of which the adapter is to be formed is then molded around the mandrel and in that portion of the axial bore of major diameter, some of such material flowing into the recesses formed in the hosel wall. After the adapter has been thus formed the mandrel is withdrawn and the handle shaft substituted for the same. The handle is then secured in place by means of the usual rivet extending through the hosel and that portion of the shaft which extends beyond the inner extremity of the adapter into that portion of the bore of minor diameter.

With these and other objects in view, the present invention consists in certain novel details of construction, and combinations and arrangements of parts, all as will be herein-after more fully described and the novel features thereof particularly pointed out in the appended claims.

In the accompanying drawings,

Figure 1 is a side elevation of a finished golf club embodying the present invention;

Fig. 2 is a sectional view of the club head hosel, as it is originally formed;

Fig. 3 is a similar view with the mandrel inserted in the hosel and the adapter molded around the same;

Fig. 4 is a similar view but with the handle shaft substituted for the mandrel and attached to the club head by the usual rivet;

Fig. 5 is a cross-sectional view on the line 5—5 of Fig. 4, more clearly illustrating the means of securing the adapter in the hosel;

Fig. 6 is a detail view showing the modified form of means for securing the adapter in the hosel.

In accordance with the present invention the hosel 10 of the club head is formed with an axle bore having a portion 11 of reduced diameter and a portion 12 of enlarged diameter near the extremity of said hosel. At the extremity of said hosel, and preferably at points spaced circumferentially thereof, there is a series of recesses or apertures 13. In the finished club the tubular metallic shaft 109

14 whose end portion conforms to the diameter of the reduced portion 11 of the axle bore within the hosel projects all the way into that portion, extending beyond the inner 5 extremity of the adapter 15 which surrounds said shaft throughout the enlarged portion 12 of said axial bore and for some distance along the shaft beyond the end of the hosel. This adapter is formed in situ of a plastic 10 non-metallic material, such as celluloid, pyroline, bakelite, etc., and during the formation of the same in situ in the club head hosel, a portion of such material flows into the recesses 13, forming interlocking projections 16 15 on said adapter. For securing the shaft itself into the club head hosel there is a rivet 17 extending through the hosel and the end of said shaft projecting beyond the inner extremity of the adapter. In this way an 20 adapter of maximum strength is provided. The rivet 17 is spaced from the adapter instead of extending therethrough and by forming the interlocking projection 16 integrally with the adapter it is unnecessary to 25 utilize fastening means of any nature whatever that might tend to cause a splitting of the adapter. Furthermore, an absolutely close fit of the adapter, both with respect to the exterior surface of the shaft and the interior 30 surface of the hosel, is insured by molding the adapter in situ in forming the connection.

In lieu of the axially extending recesses 13 spaced circumferentially of the hosel an arrangement such as shown in Fig. 6 may be utilized. In this form of interlocking connection between adapter and hosel the end of the hosel is formed with longitudinally extending recesses 13a such as are used in making a dove-tailed joint. These recesses, in both forms of the invention, may extend the full thickness of the wall of the hosel although this is not absolutely essential.

In carrying out the present method of applying the handle shaft to the club head after it has been formed as shown in Fig. 2 with the axial bore of two different diameters, a mandrel 18 is inserted all the way into the hosel and a retainer 19 placed around the portion 45 of the shaft adjacent the extremity of the hosel. The plastic material constituting the adapter is then molded, being deposited in the space between the mandrel and portion 50 12 of the enlarged diameter of the hosel, a sufficient quantity of this material being used to completely fill such space and retainer 19 as well as the recesses 13 or 13a. After the adapter has been thus formed, the mandrel 18 and the retainer 19 are removed and the handle 55 shaft, that is to be used in the club, substituted for said mandrel and fastened in the club head by the insertion of the rivet 17 through apertures previously formed in the hosel and the end of the shaft. As a final 60 step, in dressing or finishing the club, that 65

portion of the adapter projecting beyond the hosel is cut away or reduced to a taper-like cross-section, tapering away from the end of the hosel to a comparatively fine edge at its upper extremity. This gives the club a very 70 neat appearance.

As at present contemplated, it is proposed to introduce the material constituting the adapter into retainer 19 and then place it under pressure to force the same over into 75 hosel 10 and around mandrel 18. For convenience the retainer may be made in sections to facilitate its removal and if desired its cross-sectional configuration may conform to that desired for the finished adapter, thereby 80 eliminating the trimming down of the adapter as a finishing step. While non-metallic materials are believed preferable for the adapter, metals, such as aluminium may be used if desired. One feature of non-metallic 85 materials is that different colored adapter can be made, thereby giving the finished club a rather pleasing appearance.

What I claim is:

1. The hereindescribed method of applying 90 handle shafts to golf club heads which consists in forming an axial bore in the hosel of said head and recesses in the wall of said bore, inserting a mandrel in said bore, molding an adapter in said bore and recesses with 95 the mandrel therein, substituting the handle shaft for said mandrel after said adapter has been formed, and finally securing said shaft in said hosel.

2. The method of applying handle shafts 100 to golf club heads which consists in forming an axial bore in the hosel of said head, inserting a mandrel in said bore, molding an adapter in said bore with the mandrel therein, substituting the handle shaft for said mandrel after said adapter has been formed, and securing said adapter in said bore and said shaft in said hosel beyond the inner end of 105 said adapter.

HERBERT C. LAGERBLADE. 110
